UNITED STATES PATENT OFFICE.

LOUIS J. KUTZ, OF CLEVELAND, OHIO, ASSIGNOR TO THE FANNER MANUFACTURING COMPANY, OF CLEVELAND, OHIO, A CORPORATION OF OHIO.

CORNER-FASTENING FOR BEDS.

No. 853,927.

Specification of Letters Patent.

Patented May 14, 1907.

Application filed December 12, 1906. Serial No. 347,509.

To all whom it may concern:

Be it known that I, LOUIS J. KUTZ, a citizen of the United States, residing at Cleveland, in the county of Cuyahoga and State of Ohio, have invented certain new and useful Improvements in Corner-Fastenings for Beds; and I do hereby declare the following to be a full, clear, and exact description of the invention, such as will enable others skilled in the art to which it pertains to make and use the same.

My invention relates to corner locks, more especially adapted for bed-steeds, and for locking the side rails to the head and foot portions of a bed.

The object of my invention is to provide a corner lock which is reversible relative to its male portion which is secured to the side rails of the bed, thus allowing the side rails, when formed of angle iron, to present the flat upper surface, or present the edge of one of the members of the angle outward, with the other member of the angle iron or piece projecting inward, thus forming a seat. It being sometimes desired to so connect the rails at the head and foot that either of the above mentioned dispositions can be made.

Another object of this invention is to provide a corner lock, the male portion of which, or hook portion of which, may be attached to the angle piece forming the side rail, by providing an angular projection on said hook or male member, and forming the same of malleable metal. The recess having free edges which over-hang in such a manner that when turned upon the edge of the angle piece of the side rail of the bed, this part of the lock can be secured thereto without the necessity of riveting, or other means of fastening.

Still another object of this invention is to provide a lock, by means of which a side rail can be secured quickly to the head and bottom of a bed-frame, at or near the corner posts thereof, and when so secured the bed is rigid at its connected portions, and cannot, except through manual interference, become either loose or unlocked. This lock, however, may be easily loosened when it is desired to "take down" the bed.

My invention consists in the peculiar construction of the lock whereby the above objects are attained, all of which will be herein-after fully set forth and claimed.

In the drawings Figure I, is a view illustrating that portion of the corner lock which is secured to the head or foot of the bed, at or near each corner thereof. In the case illustrated, being adapted to be secured to the corner posts or either head or foot of an iron or brass bed, and hence being provided with a socket for the reception of such posts. Fig. II, illustrates that portion of the corner lock which is provided with the male member of the lock, which in turn is received within the part illustrated in Fig. I. Fig. III, is a top plan view of the lock showing the two parts of the same in interlocked position. Fig. IV is a vertical cross section taken through Fig. I on line 4—4 and through Fig. II, on line 4—4 illustrating more clearly the construction and arrangement of the interlocking parts.

A represents the corner piece forming the female portion of the lock which is preferably provided with an orifice *a*, for the reception of the corner upright, at either the head or foot of the bed. However in manufacturing the beds, the portion A may be cast around the corner posts, which in some cases is the preferable mode of construction. The part A may also be provided, as illustrated in the drawings, with an angular projection or other shaped projection, such as A' for the attachment of the connecting rail of the head or foot of the frame.

The corner lock portion of the part A, is formed with an opening B, said opening being provided with inwardly and oppositely facing flanges *b' b'*, the same being formed in vertical line, adapted to receive the edges *d, d'*, of the male portion D of the lock. This portion D forming an interlocking means with the part A.

The part A is formed with downward, forward, and inwardly projecting ribs or cleats, *a²* which form an angular or wedge shaped pocket, adapted to receive and retain the wedge-shaped piece *d², d³*, provided on the part B at both ends thereof. Thus it will be seen that either end of the part C may be entered into the part A, allowing of the reversal of the rail, and inasmuch as the flat portion of the part C, at the ends of the rail are approximately at right angles to the side rail, and the angular portions *d², d³*, incline inward from the center portion. When the

parts are interlocked the face portion of the part D is forced into engagement with the interior of the flanges b , b , thus forming and retaining a rigid contact and a perfect lock.

5 The downward pressure on the bed drives it tighter in contact with the parts, rendering the bed firm and rigid as more weight is put upon it.

Inasmuch as it is objectionable in corner locks to leave any noticeable aperture at the connecting portions of said rails at the head or foot of the bed, which renders the bed less neat in appearance and forms a receptacle for dirt and vermin, I have preferred to form 10 the opposing face or inclined face, d^2 , d^3 of the male portion in the form of ribs located at each edge, leaving the intervening portion between the two ribs flat and approximately parallel with the inner face. In the female 15 portion of the corner lock I have provided a projection a^3 which projects against said outer face of the male portion, as illustrated in Figs. I, III, and IV, and acts both as a guide during the interlocking of the parts, 20 and as a bed to the outer portion of the male part. This projection a^3 being centrally located leaving recesses a^4 — a^4 at each side to allow of the passage of the inclined ribs. The projection a^3 covers the upper portion of the 25 part A, at this point, and prevents the accumulation of dirt, and the entrance of vermin.

30 By constructing a lock as illustrated and as

above described, I provide a corner connection for beds, which is practically dirt proof, and vermin proof, and one which on account 35 of its construction prevents any swaying or movement of the parts.

The male portion C of the lock, closes the opening C from top to bottom, this prevents the accumulation of dust and vermin. 40

Thus it will be seen as hereinabove stated that I have constructed a dust and vermin proof lock, and a lock which is self tightening according to the weight put upon it, and one which can be easily locked and unlocked 45 without the use of tools.

What I claim is:—

A corner lock for bed-steeds comprising a side rail, having at its ends male members having inner flat faces, and double beveled 50 outer faces, in combination with a female member secured to the head or foot posts of the bed, said female member being provided with means for receiving and retaining the male member, comprising front flanges and 55 a rear rib, substantially as set forth.

Signed at Cleveland in the county of Cuyahoga and State of Ohio, this 10th day of December 1906.

LOUIS J. KUTZ.
